UNITED STATES PATENT OFFICE

LYMAN C. HUFF, OF CHICAGO, ILLINOIS, ASSIGNOR TO UNIVERSAL OIL PRODUCTS COMPANY, OF CHICAGO, ILLINOIS, A CORPORATION OF SOUTH DAKOTA

ORCHARD HEATER

Application filed June 18, 1927. Serial No. 199,643.

The present invention relates more particularly to an improved and novel type of orchard heater of the magazine self-feeding type particularly adapted to the burning of 5 petroleum coke.

An orchard heater should be designed to eliminate as far as possible all radiation of heat into the atmosphere since radiant heat is considered lost and is not effective in heating the air as it passes through it into space. The heating must, therefore, be accomplished by convection, that is, by causing the air to pass over hot surfaces so shielded as to decrease or prevent radiation. It should 10 also be so designed that without refilling with fuel, it can be fired harder during the 15 early morning hours when the greatest heat load is required.

These features are embodied in and constitute some of the advantages of the orchard heater of the present invention.

Some of the features of the present orchard heater comprise (1) the hot surfaces of the combustion chamber are shielded to 25 prevent loss of radiant heat; (2) all heating is done by convection and by causing a flow of air to pass over the hot surfaces; (3) the magazine holds a supply of fuel which automatically gravitates into the combustion 30 chamber as fast as the fuel therein is consumed; (4) by regulation of the means for admitting a combustion supporting medium, such as air, the amount of combustion can be accurately regulated; (5) the heat load 35 may be regulated by a simple mechanism, and particularly in the early morning it is sufficient to open the draft and admit desired quantities of combustion supporting medium, such as air, to effect greater combustion.

Various fuels may be used in this heater, but as a feature of the invention, it is particularly designed for burning petroleum coke, including fines which has high heating 45 value and almost negligible ash content.

Petroleum coke has proven to be a very desirable fuel for use in a device of this kind.

Other advantages of my invention will appear from the following description and 50 from the attached drawing, in which

Fig. 1 is a side elevational view of a type of heater embodying the features of the present invention, with certain parts broken away; and

Fig. 2 is a transverse sectional view taken on line 2—2 of Fig. 1.

I have illustrated in the drawing a type of orchard heater embodying the features of my invention, and it is understood that 60 changes may be made in the mechanical structure without departing from the scope of the invention.

Referring more in detail to the drawing, the orchard heater comprises a magazine or supply chamber 1, which may be charged with fuel to be burned, such as coke, through manhole 2, which latter may be covered with removable cap 3 with which may be associated a controllable ventilator 4. The 70 bottom of the magazine or supply chamber 1, which is tapered as shown at 5, may be connected through an inclined feed pipe 6 to the combustion chamber 7, which may comprise a vertically disposed conduit constructed of material resistant to corrosion and non-oxidizing, such as Duraloy, Askaloy, or the like. This conduit may have a diameter of 5 to 15 inches more or less. The lower portion thereof forms an ash-pit 8, 75 being separated from the combustion chamber proper by a grate 9 which may be supported by suitable means, such as a circular collar or lugs, illustrated diagrammatically at 10, and over which may be positioned some refractory material 11, such as layers of balls or turnings, to protect the grate 9 from the intense heat of the burning fuel.

On the lower wall of the vertically disposed conduit 7, below the grate 9 and pref-

erably adjacent the ash-pit 8, may be provided a manhole 12 closed by means of a movable cap with which is associated a controllable ventilator 13 through which air or other combustion supporting medium 5 may be admitted in regulated quantities under the grate. The ashes produced by combustion also may be removed through this opening by manipulating the cap in an obvious manner. The grate 9 may be of the shaking type or any other suitable type.

It is to be noted that the feed pipe 6 opens into the combustion chamber above the grate 9 and at some distance thereabove.

Over the top of the open ended combustion conduit 7, and at some distance therefrom, may be positioned an umbrella-like cap 14 which may be associated with the conduit 7 by any well known means which 15 permits adjustable movement of the cap 14 relative to the stationary conduit 7.

In one mode of operation, the fuel feeds by gravity from the magazine 1 through the feed pipe 6 onto the grate 9 in the combustion conduit 7. The fuel is ignited and the 20 combustion gases ascend through the combustion conduit 7 and through the space between the open end of said combustion conduit and the cap 14. The amount of combustion which takes place may be accurately 25 regulated by the amount of air or other combustion supporting medium which is permitted to be introduced through ventilator 13, the draft being from the ventilator 13 to the space below the cap 14. It is to be noted 30 that when it is desired to decrease combustion, or shut the fire down altogether, the cap 14 may be lowered to a position where it fits flush with the upper end of the conduit 35 7, the ventilator 13 being closed, resulting in closing the stack.

That portion of the combustion conduit 7 which extends from the grate 9 upward 40 may be surrounded with a shield 15 supported by suitable lugs 16, the object of this shield being to decrease or prevent radiation 45 of the heat from the combustion chamber to the atmosphere and to localize the heating of air around the combustion chamber 7. The 50 air to be heated circulates between the outer wall of the combustion conduit 7 and the inner wall of the shield 15 in the annular space between these elements, the convection 55 so set up causing efficient heating of the air ascending in contact with the hot surfaces of the combustion conduit 7.

Over the top of the shield 15 and at some distance therefrom, the chamber 7 may be 60 provided with an external slidable sleeve 17 which may take the form of an umbrella-like baffle. The baffle 17 may be adjusted at any distance from the top of the shield 15. The heated air escaping from the top of the heating space is deflected by means of the 65 baffle 17 out into the surrounding atmos-

sphere, being thereby prevented from going straight upward and losing its effect in the orchard.

As a feature of the present invention, it is to be noted that the fuel supply chamber 1 70 is separated from the combustion chamber 7 and, in addition, it should be noted that the hot gases of combustion do not pass through the reserve supply of fuel, thus substantially avoiding the distillation of unconsumed 75 products of combustion in the form of smoke, soot, etc.

As the consumption of fuel proceeds during the operation, additional fuel will be supplied by gravity, and automatically, to 80 the bed above the grate 9 from the chamber 1 through the supply pipe 6, it being obvious that the supply chamber 1 may be charged at suitable intervals.

From the foregoing, it will be apparent 85 that once combustion is started, it proceeds with little care and attention, being very accurately controlled by means of the draft heretofore explained.

I claim as my invention:

1. An article of manufacture comprising 90 a vertically disposed cylindrical tube of uniform diameter mounted on a flat base, a grate near the bottom of said tube, a second tube of larger diameter coaxial therewith and extending upward above said grate, a third straight cylindrical tube of smaller diameter passing through said second tube terminating in the first tube and inclined upwardly therefrom and means for supporting the 95 outer end of said inclined tube from said base.

2. An orchard heater comprising a straight vertical cylindrical tube of uniform diameter, a grate near the bottom thereof 100 forming a combustion chamber thereabove and an ashpit therebelow, means for guiding an annular stream of air upward along the outer sides of said tube above the grate to be heated by said chamber, means for deflecting 105 this annular stream radially outwardly and then slightly downwardly to distribute it for heating an orchard by convection.

3. An article of manufacture comprising 110 a vertically disposed cylindrical tube of uniform diameter, a grate near the bottom of said tube, forming a combustion chamber thereabove and an ashpit therebelow, a shield of uniform diameter larger than the tube arranged coaxial therewith located entirely above said grate and extending vertically beyond said combustion chamber, means for supporting said shield from said tube, an annular deflector secured to the outside of said tube above the top of said shield 115 and extending outwardly from said tube.

4. A portable device for heating orchards comprising in combination a vertical cylindrical stack of uniform diameter for conducting products of combustion, an open 120

ended shield surrounding said stack and spaced therefrom to prevent radiation and direct an upward current of air warmed by passage therethrough, an adjustable deflector supported above the upper end of said shield and adapted to distribute said heated air currents in a generally horizontal and downward direction from said deflector.

In testimony whereof I affix my signature.

LYMAN C. HUFF.
